UNITED STATES PATENT OFFICE

2,472,647

DOUBLE-ACTING RECIPROCATING PUMP

Meyer Covins, Danville, Ill.

Application May 9, 1945, Serial No. 592,814

1 Claim. (Cl. 103—175)

1

This invention relates to a pump and more particularly to a pump for pumping or compressing gases in an efficient and economical manner. While the pump of this invention is particularly adapted for pumping gases because of its high efficiency it may also be used to pump liquids. A pump efficient for pumping liquids is not necessarily efficient for pumping gases but an efficient gas pump is necessarily efficient for pumping liquids.

It is an object of this invention to provide an improved reciprocating type pump actuated by a crank.

It is a further object of the invention to provide a novel arrangement in construction whereby an interconnected double headed and double acting piston is actuated by a crank and the lubrication accomplished by a splash system.

It is another object of the invention where it is important in pumping gases to prevent excess lubricating oil being discharged with the gas, to provide a novel arrangement of oil rings and interconnection between the piston heads. In some cases it is desirable to use a felt oil soaked pad attached to the piston which lubricates the piston in the form of a spray rather than by the splash method.

Still another object of the invention is to provide an improved arrangement of the inlet and outlet valves which results in a more efficient pump and which is necessary for pumping gases which are more difficult to pump efficiently than liquids.

It is also an object of the invention to provide a small compact pump of large capacity which is economical to build and to operate.

A further object of the invention is to provide an arrangement of the actuating crank so as to take as little space as possible leaving more room for the pistons thereby increasing the efficiency several hundred percent over previous gas pumps.

It is also an object of the invention to provide a rotatable contact associated with the mechanical means actuating the piston which greatly reduces the friction and makes the pump more efficient.

Generally the invention involves a compact cylinder having a doubleheaded interconnected piston arranged to reciprocate in the cylinder, said piston having a slot in the center thereof with its longitudinal dimension at right angles to both the direction of reciprocation of the piston and to the axis of a crank operatively associated in said slot for reciprocating the piston when the crank is turned. The particular driving means

2

for turning the crank is not important to this invention since a motor, engine or any other suitable prime mover may be used.

The same problems are not involved in providing for an efficient gas pump as in a liquid pump. The problems are more difficult and not as easily solved. It is more difficult to have sufficient tolerance between the piston and the walls of the cylinder and yet prevent leakage. It is more difficult to lubricate and care must be taken to provide proper inlet and outlet valves for efficient operation which is not so critical for a liquid pump.

The pump in the present invention has many uses. One of its most important uses is as a tractor pump wherein the crank in the pump is attached to the power take off of the tractor motor and used as an air compressor. It can also be attached to trucks and automobiles as a tire pump. It may also be used as an air compressor pump in filling stations and the like. The pump is compact and efficient so that it can be used as a portable pump wherever a gas compressor is desired.

My pump may also be used as the source of compressed air in spray guns for spraying insects, fruit trees, paint and the like.

One big advantage of my pump is that low friction loss permits the pump to be driven by a pulley and belt whereas in previous pumps of this kind because of high friction losses a positive drive like a chain was required.

Another advantage of this pump is in the novel arrangement of the piston and crank permitting the use of a straight pipe or casting which makes the pump simple and economical to construct.

Other advantages, objects and uses of the pump will become apparent by referring to the drawings in which Figure 1 is a cross sectional perspective view of the pump assembly; Figure 2 is a perspective drawing of one type of double headed interconnected piston which may be used; Figure 3 is another type of double headed interconnected piston particularly suitable where it is important to insure that no excess lubricating oil is discharged along with the compressed gases. Figure 4 is a perspective view of the half crank.

Referring to Figures 1 and 2 cylinder 10 having heads 11 threaded thereon is provided for containing the piston 14. This pump is primarily designed to lie in a horizontal position while being used and it may be in the horizontal position as shown in Figure 1.

In heads 11 of the cylinder 10 are provided 55 inlet valves 12 shown as tappets although other

suitable types may be used. Also in the heads 11 are discharge valves 13 which are of the ball-check type although any other suitable conventional type may be used within the scope of the invention. Although not shown the two discharge valves 13 may be connected to a common heater so as to have a uniform flow of the gas compressed by the double acting piston.

Piston 14 having heads 15 and 16 interconnected by the connecting element 17 provides the moving element in the pump for the compression of the gases. Heads 15 and 16 are provided with a number of grooves in which are placed suitable piston rings and oil rings such as piston rings 18 and oil rings 19. Also slots 20 may be provided with a piston ring or compression ring although such a ring is left out of the drawing in order to show the construction of the grooves in the piston heads. A slot 21 in the center of the piston in the connecting element 17 is provided with oil openings 22. The slot does not extend entirely through the piston or the connecting element 17 although it is within the scope of the invention to do so and in that case the extended opening takes the place of openings 22. The bearing slot 21 is at right angles to the direction of reciprocation of the piston and also at right angles to the axis of crank 24. Slots 22 permit lubricating oil to enter the slot 21 for lubricating the rotatable bearing associated with the slot.

The oil rings 19 that are somewhat similar to compression or piston rings 18 with exception that they have openings therein for permitting lubricating oil to return to the bulk source rather than being forced out through the discharge valves. Openings 23 are provided in the piston heads to connect with openings in the oil rings, to drain excess oil back into the bulk supply. Openings 23 are right angle openings as indicated to drain the excess oil back into the bulk supply of oil contained between the inner faces of the piston heads, thereby preventing excess seepage toward the discharge valves. Oil is introduced into the cylinder through a screw plug at the top which is not shown since this is a well known method for lubricating cylinders. The reciprocating motion of the pump splashes the oil in such a manner that the piston is properly lubricated and also splashes the oil through the opening 22 into slot 21 so as to lubricate the rotatable bearing therein. This is known as the splash system of lubrication.

Half crank 24 is provided made up of sections 25 and 26. The half crank is preferably made in two sections for ease in assembling and although it could be made in one piece, it would be more difficult to construct and more complicated to assemble. Also it is within the scope of the invention to make the crank in three sections or parts. The two sections 25 and 26 are joined by a threaded connection as shown. The section 25 has a larger section or shoulder thereby forming a bearing surface on the annular boss 27 extending on the outside of the cylinder. The semi-spherical portion 28 of section 26 also is enlarged to provide a bearing surface on the interior of the cylinder as indicated at 29. The remaining part 30 of section 26 is the portion of the crank operatively associated in the slot 21 which causes the cylinder to reciprocate when the crank is turned. A sleeve bearing 31 is placed around this section of the crank 30 so as to freely rotate in the slot 21 providing a rotary driving action when the crank is turned greatly reducing the friction over any other bearings previously used in pumps of this type. Although not shown in the drawing, end

5 32 of the crank may be attached to any mechanical means such as a power take off of a tractor or motor for turning the crank which causes the piston to reciprocate. It may be driven by a belt connected to a pulley end 32.

Figure 3 illustrates another shape of piston and is similar to the piston illustrated in Figure 2. It is adapted to insure that the excess lubricating oil from the splash system does not work its way 10 past the oil in the piston rings so as to be discharged through the valves along with the compressed gas. Furthermore it provides an easier means for drilling the openings 34. Openings 23 in the piston of Figure 2 are right angle openings 15 which involve two operations in the drilling of the holes whereas the holes 34 in the piston shown in Figure 3 extend directly through the piston to the oil rings and may be made in one drilling operation. The connecting element 17 which connects 20 the two heads 15 and 16 of the piston in Figure 3 is cut away and fixedly attached to a recess in the cylinder heads as shown. The solid bearing surface extending between the heads of the piston in Figure 2 is thereby eliminated by the construction 25 shown in Figure 3 which prevents the excess oil from being driven in the direction toward the exhaust valves as is the tendency in the construction shown in Figure 2.

Another means for lubrication, which has certain advantages, is the provision of a pad made of felt or other material having absorbing properties which is attached on the side of the connecting element 17 opposite the openings in the back wall of the slot 21. Through the oil plug in 30 cylinder 10, lubricant is poured on the felt pad and the reciprocating movement of the piston causes the oil to form a fine spray or mist thereby lubricating the piston. The fine mist also enters 35 through the openings 22 to lubricate that bearing area. The fine mist or spray in this system minimizes the tendency of the oil to work its way towards the exhaust valves as is the case in other systems of lubrication.

It is also within the scope of this invention to 45 use a roller bearing in place of the sleeve bearing 21. A roller bearing may also be used within the boss 27 to reduce the friction of the crank turning in the boss.

It is also within the scope of my invention to 50 lubricate the pump in the following manner. Instead of having the oil reservoir contained between the inner faces of the two piston heads, the piston can be a straight cylinder hollowed out in the center and the oil supply contained in the hollowed out portion. The oil lubricates the exterior surface of the piston and the interior surface of the cylinder through holes bored through the piston wall to the oil supply. The movement of the piston will splash sufficient oil 55 through the holes to obtain the desired lubrication. By this system the amount of lubrication can be controlled by the size, spacing and number of the holes. Furthermore lubrication can be obtained at the desired and proper points by the suitable positioning of the oil holes. It may be desirable to lubricate certain portions of the pump more than other portions and this also can be controlled by the size, number and position of the oil holes. One of the advantages of this 60 type of lubrication over the usual type of splash system is that there is no oil pool in the bottom of the cylinder which tends to work past the piston and oil rings toward the exhaust valves. Furthermore, in the usual splash system, it is 65 70 75 not possible to control the amount of oil cover-

ing the bearing surfaces as is the case in this method of lubrication. While this method of lubrication is particularly adaptable for horizontal pumps and motors, it also is advantageous for use in lubricating any type of moving part like a piston.

The above description of the drawings is given as an example and is not intended to limit the invention which is only limited by the following claim.

I claim as my invention:

In a pump, a tube of uniform internal diameter throughout its length forming a cylinder, a piston therein having two longitudinally spaced heads connected by a longitudinally extending web having a thickness substantially less than the internal diameter of said cylinder, a slot in said web extending at a right angle to the longitudinal axis of the piston, a hollow boss extending outwardly from the wall of said cylinder forming a bearing, a shaft journaled in said bearing and extending into the interior of said cylinder, a crank arm removably secured to the inner end of said shaft and positioned between said web and the inner wall of said cylinder, the surface of said crank arm adjacent the inner wall of said cylinder being of curved configura-

tion to provide clearance between said crank arm and the curved inner wall of said cylinder while said crank arm is at a right angle to the longitudinal axis of said cylinder during rotation of said shaft and crank arm, and a crank pin on the free end of said crank arm positioned in said slot.
